CLAIM

The ornamental design for a personal computer, as shown and described.

DESCRIPTION

FIG. 1 is a perspective view of top, front and right side of a personal computer showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is a partially enlarged perspective view taken along line A—A and B—B n FIG. 1.

Broken lines shown in the drawings illustrate portions of the personal computer, and form no part of the claimed design.

1 Claim, 8 Drawing Sheets

FIG. 2
